UNITED STATES PATENT OFFICE

171,569

HELICOPTER

Stefan Apostolescu, New York, N. Y.

Application May 4, 1953, Serial No. 24,843

Term of patent 14 years

(Cl. D71—1)

To all whom it may concern:

Be it known that I, Stefan Apostolescu, stateless, residing at New York City, county of New York, and State of New York, have invented a new, original, and ornamental Design for a Helicopter, of which the following is a specification, reference being had to the accompanying drawing, forming part thereof.

Fig. 1 is a top plan view of a helicopter showing my new design.

Fig. 2 is a side elevational view thereof.

Fig. 3 is a front elevational view thereof.

Fig. 4 is a rear elevational view thereof.

I claim:

The ornamental design for a helicopter, as shown.

STEFAN APOSTOLESCU.
